U.S. Appl. No. 12/659,875, filed Mar. 24, 2010, entitled "Animal Cooling Device and Method Therefor".

Primary Examiner—Susan Moon Lee

(74) Attorney, Agent, or Firm—Dinesh Agarwal, P.C.

(57) **CLAIM**

The ornamental design for an animal cooling device, as shown and described.

DESCRIPTION

FIG. 1 is a right perspective view of an animal cooling device showing our new design;

FIG. 2 is a left side view of the animal cooling device of FIG. 1;

FIG. 3 is a top plan view of the animal cooling device of FIG. 1;

FIG. 4 is a bottom plan view of the animal cooling device of FIG. 1;

FIG. 5 is a front elevational view of the animal cooling device of FIG. 1;

FIG. 6 is a rear elevational view of the animal cooling device of FIG. 1; and,

FIG. 7 is a perspective view of an animal cooling device of FIG. 1, shown in use.

The portions depicted in broken line are not claimed.
